[57] CLAIM

The ornamental design for an architectural strobe fixture yoke, as shown and described.

DESCRIPTION

FIG. 1 is a front view in elevation of the architectural strobe fixture yoke of my design;

FIG. 2 is a rear elevation view thereof;

FIG. 3 is a right-hand side elevation view thereof;

FIG. 4 is a left-hand side elevation view thereof;

FIG. 5 is a top plan view thereof; and,

FIG. 6 is a bottom plan view thereof.

The broken lines are shown for illustrative purposes only and form no part of the claim design.
